UNITED STATES PATENT OFFICE.

CHARLES H. SEYMOUR, OF FLUSHING, NEW YORK, ASSIGNOR TO NATIONAL DRUG STORES CORPORATION, OF NEW YORK, N. Y., A CORPORATION OF DELAWARE.

DESIGN FOR A STORE-FRONT.

58,690.

Specification for Design.

Patented Aug. 9, 1921.

Application filed April 5, 1920. Serial No. 371,487. Term of patent 14 years.

To all whom it may concern:

Be it known that I, CHARLES H. SEYMOUR, a citizen of the United States, residing at Flushing, in the county of Queens and State of New York, have invented a new, original, and ornamental Design for a Store-Front, of which the following is a specification, reference being had to the accompanying drawing, forming part thereof.

The figure is a plan view of a store front, showing my new design.

I claim:

The ornamental design for a store front as shown.

CHARLES H. SEYMOUR.
